(57) **CLAIM**

The ornamental design for a removable handle light for a grill, as shown and described.

DESCRIPTION

FIG. 1 is a top left perspective view of the removable handle light for a grill of the present invention;

FIG. 2 is a bottom left perspective view of the removable handle light for a grill of the present invention;

FIG. 3 is a top view of the removable handle light for a grill of the present invention;

FIG. 4 is a right side view of the removable handle light for a grill of the present invention;

FIG. 5 is a left side view of the removable handle light for a grill of the present invention;

FIG. 6 is a rear view of the removable handle light for a grill of the present invention;

FIG. 7 is a front view of the removable handle light for a grill of the present invention; and,

FIG. 8 is a bottom view of the removable handle light for a grill of the present invention.
